UNITED STATES PATENT OFFICE.

JOHN M. WEISS, OF NEW YORK, N. Y., AND CHARLES R. DOWNS, OF CLIFFSIDE, NEW JERSEY, ASSIGNEES TO THE BARRETT COMPANY, A CORPORATION OF NEW JERSEY.

CATALYTIC OXIDATION OF ORTHO-CRESOL.

1,380,277.

Specification of Letters Patent. Patented May 31, 1921.

No Drawing.

Application filed December 12, 1919. Serial No. 344,370.

To all whom it may concern:

Be it known that we, JOHN M. WEISS and CHARLES R. DOWNS, citizens of the United States, residing at (1) 210 West 110th street, 5 New York city, and (2) Cliffside, in the counties of (1) New York and (2) Bergen and States (1) New York, (2) New Jersey, have invented certain new and useful Improvements in Catalytic Oxidation of Ortho- 10 Cresol, of which the following is a specification.

This invention relates to the catalytic oxidation of ortho-cresol and to the production of products of partial oxidation thereof. 15 It comprises the partial or selective oxidation of ortho-cresol by oxidation, either alone or mixed with diluents or by means of the oxygen containing gas in the presence of a catalyst to form salicylaldehyde, salicylic acid, or both. The invention is based upon the discovery that by subjecting ortho-cresol, C_7H_8O , to oxidation in the presence of an appropriate catalyst, and at an appropriate temperature a selective or 20 partial oxidation thereof takes place with the formation of an oxidation product or products such as salicylaldehyde or salicylic acid. We have found that under proper conditions, the ortho-cresol may be changed to salicylaldehyde or salicylic acid without 25 effecting the complete combustion of a very large proportion of the material treated. The invention may be practised by subjecting the ortho-cresol in the vapor phase to mixed with air or with oxygen either alone or admixed with other diluent gases or with 30 certain oxygen containing gases, to a suitable temperature in the presence of certain catalysts. The use of CO_2 has been found to be especially useful in this connection as 35 a diluent gas. It has been found that many oxids of metals are suitable as catalysts. More especially iron oxids, aluminium oxid and oxids of the fifth and sixth groups of 40 elements in the periodic system, and more particularly molybdenum oxid, have been found to be especially useful as catalysts in this process.

By suitably regulating the conditions such as temperature, pressure and presence of diluents and operating with proper catalysts, the degree of oxidation can be controlled whereby the ortho-cresol is oxidized

in a particular manner to an oxidation short of what is commonly known as complete 55 combustion to produce salicylaldehyde or salicylic acid.

The invention will be explained in connection with the following example, which is given for illustrative purposes. It is not 60 intended to limit the procedure to the exact details given as the process can be varied throughout wide limits without departing from the spirit and scope of the invention.

A mixture of ortho-cresol and air in the 65 vapor phase is passed through tubes at a temperature of about 250° C. to 500° C., the tubes containing molybdenum oxid deposited on crushed pumice with the result 70 that salicylaldehyde and salicylic acid are produced. Instead of introducing oxygen as oxygen of the air, oxygen gas may be used either alone or diluted with nitrogen or other inert gas; the proportion of oxygen to 75 orthocresol may be varied; the catalyst may be deposited on crushed pumice or other suitable powdered, granulated or fibrous material which is chemically inactive and acts merely as a mechanical distributor; the rate 80 at which the mixture is passed through the tubes may be regulated to suit the needs; the tubes may be varied in length or diameter or confined spaces other than tubes 85 may be used in which to place the catalyst; instead of molybdenum oxid, other compounds may be used as a catalyst. It is essential that hot ortho-cresol in the vapor phase shall come in contact with the catalyst in the presence of oxygen for the 90 proper reaction to take place. The introduction of a diluent gas is a convenient way to assist in regulation of the reaction. It has been found that the pressure may be varied throughout quite wide ranges, say slightly 95 below atmospheric up to considerably above atmospheric, with very satisfactory results.

Theoretical considerations point to one molecule of ortho-cresol to two atoms of oxygen as the proper proportion to produce salicylaldehyde from ortho-cresol, and one 100 molecule of ortho-cresol to three atoms of oxygen to produce salicylic acid from ortho-cresol. The following equations are suggested as representing the reactions which take place, although it is not desired to limit the reactions to any particular theory. The

equations are given to explain the reactions as indicated by the results obtained.

Where considerable excess of ortho-cresol is used over and above that which is oxidized, the remaining ortho-cresol will in part pass through practically unchanged and the reaction gases will be correspondingly diluted by the excess ortho-cresol present during the reaction. The nitrogen 10 of the air will have a corresponding diluent effect. Any steam, if present, will similarly have a diluent effect, for example, in case moist air, instead of dry air, is used in the process of the above specific example. Since water is practically always formed as a product some steam is present as a consequence.

The ortho-cresol used should preferably be of high purity or if admixed with impurities, it should be substantially free from impurities of a character as would prejudice the desire selective and partial catalytic oxidation.

It will be evident that various types of apparatus may be used for carrying out the process of the present invention and for bringing about the necessary contact of the reacting gases with the catalyst, and for maintaining the proper temperature for the catalytic reaction. Accordingly, we do not deem it necessary to describe in further detail such types of apparatus.

It will be evident also that the various conditions of the reaction are capable of variation. Among these conditions may be mentioned the temperature and pressure at which the reaction is carried out, the time of contact of the reactive gases with the catalyst, the proportion of catalyst to the reacting gases, and the relative proportions of ortho-cresol and oxygen and of diluent gases, such as nitrogen or CO_2 . The reaction may thus be carried out at atmospheric pressure, or at increased or diminished pressures. The oxidizing effect can be modified by further diluting the reacting gases, as by returning the air, impoverished in oxygen by the reaction, to dilute the reacting gases in the further carrying out of the process, or by mixing oxygen with the air to increase the oxygen content thereof, or by using oxygen alone without other diluent, or by using oxygen in admixture with other gases than those contained in air, etc.

It will be evident also that the time of contact of the reacting gases with the catalyst can be varied by increasing the catalytic mass or by decreasing the speed at which the reacting gases pass through or in contact with the catalyst. These and like variations

will correspondingly modify and affect the catalytic oxidation.

Salicylaldehyde and salicylic acid are apparently intermediate products of the incomplete oxidation of ortho-cresol. In the 70 operation of this process, under proper conditions, there has been found to be very little complete combustion, thus indicating that practically all of the ortho-cresol which is oxidized is changed to salicylaldehyde or 75 salicylic acid. Any of the ortho-cresol which passes through the process unchanged may be separated from the other products by sublimation, crystallization, distillation, etc., and may be again passed 80 through the reaction zone mixed with oxygen or mixed with a sufficient supply of ortho-cresol and oxygen, if desired, and more of it will be oxidized.

We claim:

1. The method of producing salicylaldehyde and salicylic acid which comprises oxidizing ortho-cresol in the vapor phase with an oxygen containing gas in the presence of a metallic oxid as a catalyst.

2. The method of producing salicylaldehyde and salicylic acid which comprises oxidizing ortho-cresol in the vapor phase with an oxygen containing gas in the presence of molybdenum oxid as a catalyst.

3. The method of producing salicylaldehyde and salicylic acid which comprises oxidizing ortho-cresol in the vapor phase at a temperature from about 250° C. to 500° C. with an oxygen containing gas in the presence of a metallic oxid as a catalyst.

4. The method of producing salicylaldehyde and salicylic acid which comprises oxidizing ortho-cresol in the vapor phase at a temperature of about 250° C. to 500° C. 105 with an oxygen containing gas in the presence of molybdenum oxid as a catalyst.

5. The method of producing salicylaldehyde and salicylic acid which comprises oxidizing ortho-cresol in the vapor phase with 110 an oxygen containing gas in the presence of a metallic oxid as a catalyst, separating the salicylaldehyde and salicylic acid from any unchanged ortho-cresol and returning the ortho-cresol for a similar oxidizing treatment.

6. The method of producing salicylaldehyde and salicylic acid which comprises oxidizing ortho-cresol in the vapor phase with an oxygen containing gas in the presence 120 of molybdenum oxid as a catalyst, separating the salicylaldehyde and salicylic acid from any unchanged ortho-cresol and returning the ortho-cresol for a similar oxidizing treatment.

7. The method of producing salicylaldehyde and salicylic acid which comprises oxidizing ortho-cresol in the vapor phase with an oxygen containing gas in the presence of a metallic oxid as a catalyst, at a tempera- 130

ture of from about 250° C. to 500° C., separating the salicylaldehyde and salicylic acid from any unchanged ortho-cresol and returning the ortho-cresol for a similar oxidizing treatment.

8. The method of producing salicylaldehyde and salicylic acid which comprises oxidizing ortho-cresol in the vapor phase with an oxygen containing gas in the presence 10 of molybdenum oxid as a catalyst, at a

temperature of from about 250° C. to 500° C., separating the salicylaldehyde and salicylic acid from any unchanged ortho-cresol and returning the ortho-cresol for a similar oxidizing treatment. 15

In testimony whereof we affix our signatures.

JOHN M. WEISS.
CHARLES R. DOWNS.
